(57) **CLAIM**

The ornamental design for a display screen with transitional graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

Display screen with transitional graphical user interface

1.1 is a front view of a display screen with transitional graphical user interface showing a first image;

1.2 is a front view of a display screen with transitional graphical user interface showing a second image transitioning from 1.1.

The outermost rectangle broken lines illustrate a display screen and form no part of the claimed design.

The appearance of the transitional image sequentially transitions between the images shown in 1.1-1.2. The process or period in which one image transitions to another image forms no part of the claimed design.
